J. L. MORRIS,
BAG HOLDER,
APPLICATION FILED DEC. 1, 1921.

1,432,486.

Patented Oct. 17, 1922.

UNITED STATES PATENT OFFICE.

JOLLY L. MORRIS, OF CRAFTON, PENNSYLVANIA, ASSIGNOR TO THE MORRIS AUTOMATIC SCALE COMPANY, OF CRAFTON, PENNSYLVANIA, A CORPORATION OF SOUTH DAKOTA.

BAG HOLDER.

Application filed December 1, 1921. Serial No. 519,146.

To all whom it may concern:

Be it known that I, JOLLY L. MORRIS, a citizen of the United States, residing at Crafton, in the county of Allegheny and State of Pennsylvania, have invented certain new and useful Improvements in Bag Holders, of which the following is a specification, reference being had therein to the accompanying drawings.

10 This invention relates to bag holders and has for an object to provide a bag holder especially, though not exclusively adapted for use in conjunction with automatic scales and presenting new and improved features of reliability and convenience.

15 A further object of the invention is to provide, in combination with a platform having upstanding spaced struts, a sleeve properly proportioned to fill a part of the open end of a bag, with a spring offset adapted to engage within the bag and maintain the margin of the bag under tension about the sleeve.

20 A further object of the invention is to provide a sleeve of conventional hour-glass shape, the lower converging flange of which is adapted to engage within the open mouth of a bag and provide for introduction of filling material therethrough with a substantially radial yielding offset adapted to also engage within the open mouth of the bag and maintain the bag in tensional engagement with the flange of the sleeve, as noted.

25 With these and other objects in view the invention comprises certain novel parts, elements, units, combinations, constructions and functions, as disclosed in the drawings, together with mechanical equivalents thereof, as will be hereinafter more fully described 30 and claimed.

In the drawings:

35 Figure 1 is a view in elevation of the device shown upon a conventional scale platform, and

40 Figure 2 is a top plan view of the device, both of said views showing in dotted lines a bag in filling engagement therewith.

45 Like characters of reference indicate corresponding parts throughout the several 50 views.

55 While the present invention is particularly intended and adapted for use in conjunction with scales and more especially with automatic cut-off scales, it is obvious that such scales are only an adjunct to the pres-

ent invention and that any structure which would comprise a platform 10 or its equivalent with struts 11 upstanding therefrom in spaced relation will serve the purpose for the functioning of the present bag holder and that the scale base 12 and frame-work 13 are only shown to complete the assembly effect.

Upon the struts 11 a sleeve is mounted comprising an upper tapered section 14 having ears 15 thereon with set screws 16 for adjusting the vertical position of the sleeve relative to the struts 11. Beneath the section 14 and registering therewith is a section 17 reversely tapered, as shown in the drawings, 70 narrower than the section 14, although the relative widths of the sections are not essential to the present invention.

The section 16 is provided with tubular members 18 in which are slidably mounted 75 the ends 19 of a preferably U-shaped rod having substantially parallel sections proportioned and positioned to slide freely in said tubular members and with springs 20 tending to move the U-shaped member outwardly away from the sleeve.

At the end of the U-shaped member opposite the extremities 19 the sections are bent downwardly, as at 21, providing a preferably and approximately vertical section and 85 then outwardly at 22 to form an inclined section, the inclination being similar to the taper of the section 17 of the sleeve and corresponding thereto in height so that a bag indicated in dotted lines at 23, when the 90 mouth or upper edge is engaged over the section 17, may also be engaged by the section 22, which, by reason of the spring 20, will tend to hold the bag in open position with a portion of the same embracing the 95 sleeve through which material may be introduced in any approved manner, as from the chute 24.

In operation, the mouth of a bag will be held manually open and lifted under the 100 sleeve and the upper edge placed about the section 17, being drawn manually in the direction of the section 22, which will be pushed inwardly against the tension of the spring until the bag can be lifted over the 105 inclined portion 22, whereupon, by the release of the member, the spring 20 will force the section 22 to support that side of the bag holding the bag, as will be noted more particularly from Figure 2, open about the 110

sleeve and extending substantially in a triangle to and about the inclined portion 22. To release the bag, of course, the member 22 is again pushed inwardly against the tension of the spring, whereupon the bag will drop from engagement not only with such member 22 but with the sleeve.

The screw adjustment of the sleeve relative to the struts, carrying as it does also the 10 spring construction, provides means for co-acting with bags of various dimensions, so that the same filling device may be employed by a slight adjustment to fill bags of various styles, shapes, sizes and dimensions.

15. What I claim is:

1. The combination with a platform and spaced struts of a sleeve having ears embracing the struts, means to maintain the sleeve at vertically secured, adjusted positions upon 20 the struts, and an arm offset from the sleeve yielding radially relative thereto and pro-

vided at its outer extremity with means co-acting with the sleeve for supporting a bag in open position about the sleeve and the extremity of such yielding member.

2. A bag holder comprising a sleeve composed of upper and lower sections, each tapered outwardly reversely to the other, means to support the sleeve in a substantially horizontal plane, a spring controlled 30 arm extending radially outwardly from the sleeve and yielding radially relative thereto, and an inclined portion carried by the outer extremity of the spring arm corresponding with the taper of the lower section of the 35 sleeve both as to taper and vertical position.

In testimony wherof I hereunto affix my signature in presence of two witnesses.

JOLLY L. MORRIS.

Witnesses:

ERNEST PAYNE,
WILLIAM H. BUSCH.
